ATTORNEY.

UNITED STATES PATENT OFFICE.

THOMAS H. GRIGG, OF PHILADELPHIA, PENNSYLVANIA, ASSIGNOR TO ROBERT G. GRIGG, OF PHILADELPHIA, PENNSYLVANIA.

WRENCH.

1,054,687.

Specification of Letters Patent.

Patented Mar. 4, 1913.

Application filed October 5, 1911. Serial No. 653,017.

To all whom it may concern:

Be it known that I, THOMAS H. GRIGG, a citizen of the United States, residing at Philadelphia, in the county of Philadelphia, and State of Pennsylvania, have invented 5 certain new and useful Improvements in Wrenches, of which the following is a specification.

The object of my invention is to provide 10 a wrench of novel, simple and efficient construction by means of which nuts may be readily tightened or loosened on freely rotatable arbors or other loose objects.

To this end the invention consists in the 15 provision of a member having a nut-receiving opening therein and a hammer slidably connected to the member and having a part arranged to strike a blow against the member and thereby tighten or loosen the nut, 20 when the hammer is actuated by hand, as will be hereinafter described and claimed.

In the accompanying drawings, illustrating 25 my invention: Figure 1 is a perspective view of my improved wrench. Fig. 2 is a side elevation, showing the wrench applied to a nut and the hammer in position to be actuated to loosen the nut. Fig. 3 is a side elevation, showing the wrench applied to a nut and the position of the hammer after it 30 has been actuated to loosen the nut. Fig. 4 is a detail partly in section, showing the manner in which the hammer is slidably connected to the nut-engaging member.

Referring to the drawings, 2 designates 35 the nut-engaging member and 3 the hammer slidably connected thereto.

The nut-engaging member 2 comprises a flat portion 4 having a suitable shaped nut-receiving opening or socket 5 therein and a 40 shank 6 projecting from the portion 4 and having a guide opening 7 therein. In the form of embodiment of my invention shown in the drawings, the nut-receiving opening 5 is hexagonal in shape but it will be readily understood that the shape of this opening 45 may be changed to suit various requirements.

The hammer 3 comprises a heavy, elongated, cylindrical body portion 8 having a 50 rod-like projection 9 extending from one end thereof in axial alinement therewith. The projection 9 extends through and is slidably fitted to the guide opening 7 in the

nut-receiving member 2; and the free end of the projection 9 is provided with a transverse pin 10 to prevent the projection 9 from being withdrawn from the guide opening 7. The wall of the guide opening 7 is made convex in form, as shown, to permit the projection 9 to slide freely therethrough 60 and to prevent binding.

When it is desired to loosen a nut on a freely rotatable arbor, the wrench is applied to a nut 11, as shown in Fig. 2, and the hammer 3 is moved to the position there 65 shown. When the parts are in this position, the hammer 3 is moved by hand quickly in the direction of the arrow, thereby causing the main body of the hammer 3 to strike a blow against the member 2 70 and move it to the position, shown in Fig. 3 and thereby loosen the nut 11 before the loosely-mounted arbor carrying the nut responds to the blow of the hammer. It will be readily understood that when it is desired 75 to tighten a nut the member 2 should be applied to the nut in a reverse direction. The hammer 3 is made heavier than the member 2 so that the blow struck by the hammer against the member will readily 80 actuate the latter to tighten or loosen a nut; and the hammer 3 is elongated in the direction of its path of movement to receive the full benefit of its weight in striking the member 2.

It will be observed that the axis of the nut-receiving opening 5 extends through a plane substantially at right angles to a plane through which the axis of the guide opening 7 extends, so that the hammer 3 will 90 be directed by the guide opening 7 to move through a plane substantially at right angles to the axis of the nut-receiving opening 5, thereby causing the hammer 3 to act upon the member 2 in the proper direction 95 in the tightening or loosening a nut.

I claim:

1. A wrench comprising a member provided with a nut-receiving opening, and a hammer slidably connected to said member 100 and movable with relation thereto through and guided in a plane substantially at right angles to the axis of said opening and arranged to strike said member.

2. A wrench comprising a member provided with a nut-receiving opening and a 105

guide opening, the axes of said openings extending through planes substantially at right angles to each other, and a hammer having a guide extension slidably fitted to said guide opening and having a part movable into and from engagement with said member.

In testimony whereof I affix my signature in presence of two witnesses.

THOMAS H. GRIGG.
